Attorney

UNITED STATES PATENT OFFICE

WILLIAM ABRAM EVERS, OF MARTINSBURG, WEST VIRGINIA

RAILWAY RAIL JOINT

Application filed July 30, 1929. Serial No. 382,173.

This invention relates to railway rail joints, and has for one of its objects to provide a novel device of this character which shall be exceptionally strong and durable and which shall be adapted to positively hold the ends of the rails against relative vertical and horizontal movements.

To attain the foregoing and other objects, the nature of which will appear as the description proceeds, the invention comprehends the provision of a railway rail joint which shall embody thickened web extensions adapted to overlap each other between the bases and the heads of the rails.

15 The invention further comprehends the provision of a railway rail joint wherein the bases and the heads of the rails shall be provided with level seats for the level upper and lower edges of the overlapping web extensions.

20 The invention is hereinafter more fully described and claimed, and illustrated in the accompanying drawing, wherein:

Figure 1 is a top plan view of a railway rail joint constructed in accordance with my invention.

Figure 2 is a view in side elevation of this joint;

25 Figure 3 is a sectional view taken on the horizontal plane indicated by the line 3—3 of Figure 2; and

Figure 4 is a sectional view taken on the vertical plane indicated by the line 4—4 of Figure 3.

30 Referring in detail to the drawings, 1 designates the bases, 2 the webs, and 3 the heads of a pair of railway rails.

In accordance with my invention, the ends of the bases 1 and heads 2 are offset, as at 4, and the webs 2 are provided with thickened extensions 5^a. The web extensions 5^a are arranged in overlapped relation, and the web extension of one rail is arranged between the base and head of the other rail.

45 The web extensions 5^a contact with each other

at the longitudinal center of the webs 2 and extend beyond the outer or lateral sides of the webs.

These web extensions avoid the use of angle bars or separate joint bars. These web extensions extend laterally beyond the heads 3 of the rails, and they are of such length that their remote ends overlap unthickened portions of the webs 2. That is to say, the thickened web extension 5^a of one rail extends 50 beyond the thickened web extension of the other rail and contacts with the web of such rail. The web extensions 5^a are provided with openings 17 for the reception of a bolt 18, and they and the webs 2 are provided with 55 openings 19 for the reception of bolts 20.

It should be apparent that the overlapping thickened web extensions and the contacting level seats and level edges of the bases, heads and web extensions, cooperate in the manner 60 to render the joint strong and durable and to positively hold the rail ends against relative vertical and horizontal movements.

While I have described the principle of the invention together with the structures which 70 I now consider the preferred embodiments thereof, it is to be understood that the embodiments are merely illustrative and that such changes may be made, when desired, as fall within the scope of the invention as 75 claimed.

I claim:

1. In combination, a pair of railway rails provided with thickened and overlapping web extensions, the web extensions contacting 80 with each other at the longitudinal center of the webs, and the web extension of one rail fitting between the base and head of the other rail, and a retaining element passing through each web extension and engaging the web of 85 the abutting rail.

2. In combination, a pair of railway rails provided with thickened web extensions having level upper and lower edges, the web extensions contacting at the longitudinal center 90

of the webs, and the web extension of one rail fitting between the base and head of the other rail and extending beyond the web extension of such rail, level seats formed on the bases and heads for contact with the level edges of the web extensions, and fastening elements each engaging the web extension of one rail and the web of the abutting rail.

In testimony whereof I hereunto affix my
18 signature.

WILLIAM ABRAM EVERSON.
